UNITED STATES PATENT OFFICE.

LEE WILKINSON, OF SOUR LAKE, TEXAS.

LIFTING DEVICE.

1,417,436.

Specification of Letters Patent. Patented May 23, 1922.

Application filed March 2, 1921. Serial No. 449,015.

To all whom it may concern:

Be it known that I, LEE WILKINSON, a citizen of the United States, and a resident of Sour Lake, in the county of Hardin 5 and State of Texas, have invented certain new and useful Improvements in Lifting Devices, of which the following is a specification.

This invention relates to lifting devices 10 especially adapted for use in lowering and elevating pipes in wells.

An important object of this invention is to provide a device of the character described, embodying a pair of gripping sections 15 having novel means whereby the same may be detachably secured to a well pipe, so that the well pipe may be either raised or lowered without the possibility of the device becoming accidentally disconnected.

20 The invention forming the subject matter of this application has novel means whereby the sections are spread as the locking means for the same are moved to their inoperative positions.

25 A further object of the invention is to provide a device of the class described which is simple to attach, of highly simplified construction, and cheap to manufacture.

Other objects and advantages of the invention will be apparent during the course 30 of the following description.

In the accompanying drawings forming a part of this application and in which like numerals are employed to designate like 35 parts throughout the same,

Figure 1 is a side elevation of the improved device in use,

Figure 2 is a plan view of the same,

40 Figure 3 is an enlarged side elevation of the device applied,

Figure 4 is a side elevation of a latch embodied in the invention,

Figure 5 is a detail sectional view taken on the line 5—5 of Figure 3,

45 Figure 6 is a vertical transverse sectional view taken on the line 6—6 of Figure 3.

In the drawings wherein for the purpose of illustration is shown a preferred embodiment of the invention, the numerals 10 and 50 12 designate a pair of co-acting semi-circular sections provided with aligned hinge barrels 14 through which a hinge pin 16 is extended for hingedly connecting the sections.

55 The other ends of the sections 10 and 12 are formed with radial extensions 17 and

18 which are adapted to be detachably connected when it is desired to lock the sections 10 and 12 about a well pipe 20.

The means employed for locking the radial extensions 17 and 18 includes a disk-shaped latch 21 having a centrally arranged opening 22 through which the shank of a pivot element 24 is extended. The pivot element 24 is also extended through the radial extension 17. As illustrated in Figure 4, the disk-shaped latch 21 is provided with an extension 26 with which a transversely extending keeper 28 is connected. The keeper 28, which is connected intermediate 70 its ends to the extension 26, is provided with depending lugs 30 which engage the outer sides of the extensions 17 and 18 and thereby hold the extensions together. When the extensions 17 and 18 are thus held together, 75 the semi-circular sections 10 and 12 will be held in position about the well pipe so that the well pipe may be raised or lowered as desired.

A handle 33 extends upwardly from the disk-shaped portion of the latch and forms the means whereby the latch may be rotated on the pivot element for swinging the depending lugs 30 to their operative and inoperative positions. Of course, when the handle 33 is rotated in a clockwise direction to the limit of its movement, the depending lugs 30 will be engaged on opposite sides of the extensions 17 and 18 and the body portion of the keeper 28 will be received 90 within recesses in the adjacent portions of the sections 10 and 12 so that the surface of the keeper will be flush with the upper ends of the sections 10 and 12.

An arcuate cam 36 is formed integral with 95 the disk-shaped latch and extends laterally from the same, so as to contact with a shoulder 37 formed on the extension 18 whereby when the disk-shaped latch 21 is rotated in an anti-clockwise direction, the extensions 100 17 and 18 will be spread thereby separating the sections 10 and 12. The inclined edge of the cam 36 merges into the adjacent surface of the disk-shaped latch 21 so that there will be no obstacle to prevent the rotation of the latch in an anti-clockwise direction.

As illustrated in Figures 2 and 3, the extensions 17 and 18 are formed at their ends with lugs 40 which extend beyond the plane 110 or periphery of the latch so as to prevent the same from coming in contact with the

side of the well, and so as to form gripping devices whereby the hand may be securely engaged with the sections 17 and 18, when adjusting the device.

5 In attaching the device to the pipe 20 semi-circular sections 10 and 12 are arranged on opposite sides of the same and the weight of the manipulating lugs 33 and the keeper 28 will rotate the latch 21 in a clockwise direction and the lugs 28 will be engaged with the ears 17 and 18 whereby the sections 10 and 12 are locked about the pipe. As 10 illustrated in Figure 3, the coupling at the upper end of the pipe 20 contacts with the keeper 28 and thereby firmly holds the same in position so that sections 10 and 12 will be securely locked about the pipe during the elevation of the pipe and no obstacles which the device may strike will serve to 15 unlock the device.

20 With reference to the foregoing description it will be observed that the rotation of the latch in an anti-clockwise direction will unlock the sections 10 and 12 and will simultaneously spread the same, so that the device 25 may be disconnected from the pipe.

Having thus described the invention, what is claimed is:

1. A device of the character specified comprising hinged connected sections having radial extensions, and a latch of disk shaped formation arranged between the sections and pivoted to one of the sections, said latch being provided with a laterally projecting arcuate cam adapted to engage one of the sections whereby to separate the sections when the latch is rotated in one direction.

2. A device of the character specified comprising a pair of hinged connected sections 30 having radial extensions, one of said extensions being provided with a shoulder, a latch

of disk shaped formation rotatably connected to one of said sections and having its periphery provided with a laterally projecting arcuate cam adapted to engage said shoulder whereby to separate said sections, and locking means carried by said latch for engaging said extensions. 45

3. A device of the character specified comprising a pair of sections, a disk shaped latch 50 rotatably associated with one of the sections and having a handle, said disk shaped latch being provided with a laterally projecting arcuate cam having its edge beveled and adapted for engaging one of the sections 55 whereby to separate the sections, and a lifting device associated with said sections.

4. A device of the class described, comprising a pair of hinged connected sections having extensions, a disk shaped latch rotatably connected to one of said sections and having a keeper adapted for engaging said sections, a handle connected to the periphery of said latch, and an arcuate cam extending laterally from said latch and adapted for 60 engaging the terminal portion of one of said extensions. 65

5. A device of the class described, comprising a pair of semi-circular sections, provided with radial extensions having gripping devices, a disk-shaped latch rotatably connected to the inner side of one of said extensions and provided with a keeper having depending lugs adapted to engage on opposite sides of said extensions for locking the 70 extensions together, said latch being provided with a laterally projecting arcuate cam having a beveled edge adapted to engage one 75 of said extensions for moving the same outwardly, and a lifting device connected to 80 said sections.

LEE WILKINSON.
